DRUM AND SINGLE SHOE BRAKE

Fred E. Bachman, St. Louis, Mo., assignor to
 American Steel Foundries, Chicago, Ill., a corporation of New Jersey

Application July 22, 1950, Serial No. 175,460

12 Claims. (Cl. 188--33)

1

This invention relates to brakes and more particularly to a novel railway brake having unusual capacity to decelerate trains moving at high speeds.

A primary object of the invention is to devise a drum type railway brake wherein brake bands engagable with the drum are supported by the frame of a railway car truck.

Another object of the invention is to accommodate vertical movements of the supporting truck frame without moving the bands.

A further object of the invention is to devise novel supporting and torque transmitting means for the brake bands.

A different object of the invention is to devise novel actuating means for the brake bands capable of applying them under substantially equal pressure to the drum.

Another object of the invention is to devise a brake actuating system for simultaneous actuation of a drum brake and a wheel tread brake.

Still another object of the invention is to devise a novel brake drum having a readily removable friction shell mounted on its outer perimeter for engagement with associated brake bands.

The foregoing and other objects and advantages of the invention will become apparent from a consideration of the following specification and the accompanying drawings wherein:

Figure 1 is a top plan view of a railway car truck embodying the invention, only one-half of the truck being shown, inasmuch as the brake system is identical at opposite sides thereof;

Figure 2 is a side elevational view of the left half of the truck shown in Figure 1;

Figure 3 is a sectional view on the line 3--3 of Figure 1;

Figure 4 is a sectional view on the line 4--4 of Figure 1; and

Figure 5 is a sectional view on the line 5--5 of Figure 1.

In each of said views, certain details may be omitted for the sake of clarity, where more clearly seen in other figures.

Describing the invention in detail, the truck comprises a truck frame, generally designated 2, supported in conventional manner by springs diagrammatically indicated at 4, in Figure 5, said springs being mounted on an equalizer 6 adjacent the ends thereof, which are not shown for the sake of clarity, said ends being supported in the usual manner by journal boxes 8 of wheel and axle assemblies generally designated 12. Each wheel and axle assembly includes an axle 55

2

14 having a wheel 16 mounted thereon adjacent each end thereof.

As best seen in Figures 3 and 4, a brake rotor or drum, generally designated 17, is connected to the wheel and axle assembly 12 for rotation therewith, as for example by screws 18 connected to the adjacent wheel 16. Preferably, a sleeve or shell 19 (Figure 4) is sleeved on the outer perimeter of the drum 17 and is retained within a recess 20 at the outboard edge thereof by a ring 22 having a recess 24 receiving the opposite edge of the shell 19. The ring is removably attached to the drum as by screws 26.

The sleeve 19 is preferably provided with a plurality of spaced friction blocks 28 (Figures 3 and 4) secured thereto in any desired manner as for example by bonding or rivets (not shown); however, it will be understood that if desired the blocks 28 may be eliminated and the shell 19 may be provided with any desired friction surface.

Associated with each brake drum 17 is a pair of brake bands or shoes 30 having lugs 32 pivotally fulcrumed by a pin 34 to an arm 36 of a support bracket generally designated 38, said arm being removably connected, as for example by screws 40, to another arm 42 which extends outboardly of the adjacent wheel 16 and is connected to the inboard side of the related journal box 8 which, in the illustrated embodiment of the invention, is cast integral with the arm 42. Thus each brake support frame 38, as best seen in the left half of Figure 1, is generally U-shaped in plan view with the arm 36 projecting inboardly of the adjacent wheel 16 and the arm 42 projecting outboardly thereof, the wheel 16 being received between the arms of the frame 38 to afford a compact brake support structure adapted to afford a sturdy and rugged support within the space limitations inherent in a conventional railway car truck.

As best seen in Figure 2, and the left half of Figure 1, the arm 36 is provided with jaws 44 adapted to receive the fulcrum lugs 32 of the brake bands 30, said jaws having notches or recesses opening upwardly and adapted to receive loosely the pin 34, which is yieldingly held within the notches 46 by a flat plate spring 48 anchored by a bolt and nut assembly 50 to the arm 36.

The jaws 44 are embraced by jaws 52 of a torque arm 54 resiliently and universally connected to a bracket 56 on an adjacent transom 57 of the truck frame 2 by means of spaced resilient pads 58 and a nut 60 threaded on the torque arm 54 to compress the pads 58 against opposite sides of the bracket 56. The arms 52

are pivotally connected to the pin 34 by openings in said arms, as best seen in Figure 4, said openings receiving the pin 34 and being substantially complementary thereto. Thus it will be seen that the arm 54 aids in the distribution of torque to the sprung frame whereby any tendency of the journal box to bind at its diagonal corners in the related pedestals 62 is alleviated. The torque arm then functions to prevent the journal box from rotating on its axle either due to the off center loading of the support bracket 38 while the brakes are inoperative or to a combination of the off center loading of the support and braking torque when the brakes are operative.

Thus it will be understood that the truck frame 2 is a sprung portion of the truck supported by springs 4 on the unsprung equalizers 6 thereof, and as the frame 2 moves upwardly and downwardly on its supporting springs 4, the torque arm 54 pivots about the pin 34, thereby avoiding vertical displacement of the bands 30 which are supported by the unsprung brake frame 38. In this manner, the brake bands 30 are maintained in concentric relationship with respect to the drum 17. It may be noted that the frame 2 is guided, during such vertical movement, by conventional pedestal legs 62 embracing each journal box 8.

Each brake band 30 is preferably provided on its outer perimeter with a plurality of radial heat dissipating fins 64 and is also provided with a pair of actuating lugs or arms 66 above the rotational axis of the wheel and axle assembly 12, the fulcrum lugs 32, as heretofore described, being below said axis.

Wheel brake means are preferably provided for each wheel 16 in the form of a conventional truck lever 68 shown in the illustrated embodiment as a dead truck lever having a fixed pivot at 10 to the truck frame and a pivotal connection as at 12 to a brake head 14 carrying a conventional brake shoe 76 for engagement with the tread or rail engaging surface of the wheel 16. As best seen in Figure 5, each brake head 14 is pivoted to the related truck lever 68 by a tie rod 11 extending transversely of the truck for similar connection to the corresponding brake head 14 and truck lever 68 at the opposite side of the truck.

The above-described brake system is preferably operated by a conventional piston and cylinder device 78 actuated in the usual manner by compressed air and comprising a piston rod 80 pivotally connected as at 82 to a live cylinder lever 84 which is pivotally connected intermediate its ends as at 86 to a conventional slack adjuster pull rod 88 having a pivotal connection as at 90 to a dead cylinder lever 92 intermediate its ends. The dead cylinder lever 92 is pivotally connected as at 94 to a bracket 95 on the end of the cylinder 78 remote from the rod 80.

The inboard end of each cylinder lever is pivotally connected as at 96 to a link 98 having a pivotal connection as at 100 to an equalizer link 102. The outboard end of each equalizer link 102 is pivotally connected by a ring and clevis 104 (Figure 1, right) to the upper end of the adjacent truck lever 68, and the inboard end of each equalizer link 102 is pivotally connected by a link and clevis 106 (Figure 3) to the upper end of a live auxiliary lever 108, the lower end of which is pivotally connected as at 110 to a compression or push rod 112 pivotally connected as at 114 to the lugs 66 of the adjacent brake band 30.

The live auxiliary lever 108 is pivotally connected intermediate its ends as at 116 to a pull rod 118, the opposite end of which is pivotally connected as at 120 intermediate the ends of a dead auxiliary lever 122, the upper end of which is pivotally fulcrumed as at 124 to a fulcrum bracket 126 on an end rail 128 of the truck frame 2. The lower end of the dead auxiliary lever 122 is pivotally connected as at 130 to a compression or push rod 132 which is pivotally connected as at 134 to the lugs 66 of the adjacent brake band 30, whereby upon actuation of the brake system, as hereinafter described, the bands 30 clamp the related brake drum 17 therebetween.

It may be noted that the brake cylinder 78 is preferably mounted on a pad 136 on the outboard side of the truck frame 2 in what is known in the art as a unit cylinder arrangement.

Upon actuation of the above-described brake system, the piston rod 80 moves to the left, as shown in Figure 1, thereby rotating the live cylinder lever 84 about its pivot point 86 thereby actuating the brake means associated with the related wheel. Thereupon, the pull rod 118 rotates the dead cylinder lever 92 in a counter-clockwise direction about its pivot point 94 to actuate the brake means associated with the other wheel.

It will be understood that upon actuation of each equalizer link 102 by the related cylinder lever, the truck lever 68 associated therewith is operated to urge its shoe 76 against the tread surface of the adjacent wheel, and the associated live auxiliary lever 108, as best seen in Figure 3, is rotated about its pivot point 116 to exert a pushing force on the related rod 112, thereby urging one of the brake bands 30 into engagement with the drum 17, whereupon pull exerted by the rod 118 on the dead auxiliary lever 122 is effective to exert a pushing force on the rod 122 to urge the other brake band 30 against the drum 17. Thus, it will be understood that upon actuation of the power cylinder device 78, 80, both the wheel and off-wheel brake means of each wheel and axle assembly 12 are actuated to decelerate the truck.

I claim:

1. In a brake arrangement for a railway car truck, a truck frame, a supporting wheel and axle assembly including a journal box, pedestal jaws on the frame receiving said box whereby same is movable vertically relative to said frame, a rotor on the assembly, a torque rod universally connected to the frame and extending beneath the rotational axis of said assembly, a pair of bands pivoted to the rod beneath said assembly and disposed at opposite sides of said rotor, means provided on said box to support said bands, and means connected to said bands for engaging them with said rotor.

2. In a brake arrangement for a railway car truck, a truck frame, a supporting wheel and axle assembly including a journal box, said assembly and box being movable vertically relative to said frame, pedestal jaws on the frame receiving said box, a rotor on the assembly, a brake support carried by said box, an independent torque arm universally connected to said frame and projecting beneath the rotational axis of said assembly, brake bands pivoted to said arm and support beneath said axis to engage said rotor, and actuating means for said bands connected thereto above said axis.

3. In a brake arrangement for a railway car

truck having a truck frame and a supporting wheel and axle assembly; the combination of inboard and outboard brake surfaces on said assembly, inboard and outboard brake means for respective surfaces, said inboard brake means including a pair of brake bands supported by said assembly, torque resisting means universally connecting said bands to the frame, power means supported by said frame, and an operative connection between said power means and both of said brake means for substantially simultaneous actuation thereof.

4. In a brake arrangement for a railway car truck having a truck frame and spaced supporting wheel and axle assemblies; the combination on inboard and outboard brake surfaces on each assembly, inboard and outboard brake means for respective surfaces, said inboard brake means including a pair of brake bands supported by said assembly, torque resisting means universally connecting said bands to the frame, a power cylinder device supported by said frame, live and dead cylinder levers pivotally connected to opposite ends of said power means and pivotally connected to each other, and means operatively connecting each cylinder lever to the inboard and outboard brake means for the adjacent assembly.

5. A brake arrangement, according to claim 4, wherein the connection of each cylinder lever to the related inboard brake means comprises live and dead auxiliary levers pivotally connected to each other and operatively connected to said inboard brake means.

6. In a brake arrangement for a railway car truck having a wheel and axle assembly and a truck frame resiliently supported by said assembly; the combination of a U-shaped bracket carried by the assembly and including spaced arms receiving a portion of a wheel therebetween, a pair of brake bands pivoted to one arm of said support beneath the rotational axis of said assembly, and actuating means for said brake bands connected thereto at the opposite side of said axis.

7. A brake arrangement, according to claim 6, wherein means are provided for transmitting torque from said brake bands to the truck frame.

8. In a brake arrangement for a railway car truck having a wheel and axle assembly and a truck frame spring-supported therefrom; the combination of a bracket carried by said assembly outboardly of a wheel thereof, a pair of brake bands pivoted to said bracket inboardly of said wheel, a torque arm universally connecting said bands to said frame beneath the axis of rotation of said assembly, and operating means for said bands carried by said frame and connected to said bands above said axis.

9. In a brake arrangement for a railway car truck, a truck frame, and a supporting wheel and axle assembly movable vertically relative to said frame and including a rotor, a brake support bracket carried by said assembly and having a rod projecting beneath the rotational axis of said assembly, a torque arm connected to said frame and projecting beneath said axis, brake bands to engage said rotor, pivot means interconnecting said bands and arm and rod, and operating means for said bands comprising inter-

connected live and dead levers, tension rods connecting certain ends of said levers to respective bands, the opposite end of one lever being pivotally fulcrumed to the structure, and power means operatively connected to the opposite end of the other lever.

10. In a brake arrangement for a railway car truck, a truck frame, spaced supporting wheel and axle assemblies; inboard and outboard brake means for each assembly, said inboard brake means including a rotor and a pair of brake bands, interconnected live and dead cylinder levers supported by said frame, certain ends of said levers having operative connections to the inboard and outboard brake means of the respective assemblies, each of said connections comprising an equalizer having an operative connection to the related outboard means and having another connection to the related inboard brake bands, said other connection comprising interconnected live and dead auxiliary levers, tension rods connecting corresponding ends of said auxiliary levers to the related inboard brake bands, the opposite end of one auxiliary lever being pivotally fulcrumed to the truck frame and the opposite end of the other auxiliary lever being connected to the related equalizer, and power means connected to one of the cylinder levers, the other cylinder lever being afforded a fixed fulcrum to the frame.

11. In a brake arrangement for a railway car truck comprising a wheel and axle assembly having a brake surface thereon and a supported truck structure including sprung and unsprung portions; the combination of a pair of arms connected to respective portions and pivotally connected to each other, a brake mechanism pivotally fulcrumed to both arms at their point of pivotal connection, said point of connection being disposed below the axis of said assembly, and operating means for urging said brake mechanism against the brake surface of said assembly.

12. In a brake arrangement for a railway car truck having a wheel and axle assembly with a brake surface and a supported truck structure with sprung and unsprung portions; the combination of a support member carried by one of said portions and a torque transmitting member carried by the other of said portions, a brake member, means pivotally connecting said members to each other on a common pivotal axis beneath said axle, and operating means above said axle for urging said brake member against the brake surface of said assembly.
